United States Patent Office

Des. 179,670
Patented Feb. 5, 1957

179,670

COMBINED MOUNTED CAMERA AND PHOTOFLASH UNIT

Manuel Zimberoff, Ralph G. Leavitt, and Henry I. Paul,
Chicago, Ill.

Application October 3, 1955, Serial No. 38,213

Term of patent 14 years

(Cl. D61—1)

Fig. 1 is a perspective view from one side of a combined mounted camera and photoflash unit showing our new design.

Fig. 2 is a perspective view showing the side opposite to that shown in Fig. 1.

Fig. 3 is a top plan view of only the casing enclosing the camera and photoflash unit.

We claim:

The ornamental design for a combined mounted camera and photoflash unit, as shown.
